WRIST WATCH STRAP

John C. White, Williamston, N. C.

Application February 5, 1946, Serial No. 645,569

1 Claim. (Cl. 24—176)

1

My invention relates to wrist watch straps and the object of my invention is to provide a wrist watch strap which can be made entirely from stainless steel or the like.

Another object of my invention is to provide a wrist watch strap which cannot become unfastened accidentally.

Other objects of my invention may appear in the following specification describing my invention with reference to the accompanying drawing illustrating a preferred embodiment of my invention. It is however to be understood that my invention is not to be limited or restricted to the exact construction and combination of parts described in the specification and shown in the drawing, but that such changes and modifications can be made which fall within the scope of the claim appended thereto.

In the drawing:

Figure 1 is an edge view of a wrist watch strap according to my invention, a watch attached thereto being indicated in broken lines.

Figure 2 is a fragmentary plan view of the strap shown in Figure 1 detached from the watch.

Figure 3 is a sectional view taken on line 3—3 of Figure 2, and

Figure 4 is a sectional view taken on line 4—4 of Figure 2.

Referring now in detail to the drawing the wrist watch strap according to my invention consists mainly of two strips of thin resilient material, preferably stainless steel, 10 and 11 respectively. On one end of each of these strips an eye 12 is formed by means of which the strips can be attached in any conventional, well-known manner to a watch 13.

On the other end of the strip 10 another eye 14 is formed which holds pivotally a buckle 15. This buckle has a main cross piece 16 extending through the eye 14 of the strip 10. Two side bars 17 extend forwardly from and at right angles to the main cross-piece 16 and are formed preferably integrally with said cross-piece. On their ends the side bars are bent inwardly at right angles as shown at 18, and then downwardly to form short locking prongs 19. Midway between the main cross-piece 16 and the inwardly extending ends of the side bars 17 a center cross-piece 20 extends between the side bars and is rigidly fastened thereto. A loop-shaped keeper 21 is slidably mounted on the strip 10.

The free end of the other strip 11 is preferably tapering as shown at 22 and adjacent this end strip 11 is provided with one or more locking protuberances 23. When a plurality of protuberances are employed, the protuberances protrude upwardly on strip 11, extend transversely thereof and are arranged symmetrically to the longitudinal center line of the strip 11.

At a distance from the protuberance 23 and between the eye 12 on strip 11 and said protuberance a plurality of pairs of locking holes 24 are provided, adapted to selectively receive the locking prongs 19 of the buckle 15.

2

When a strap according to my invention is attached to a watch and is to be secured to a wrist the tapered end 22 of strip 11 is inserted in the buckle 15 between the ends 18 and the center cross-piece 20 so that the ends 18 will be on top of and the cross-piece 20 below the strip 11. Then the tapered end will extend over and above the main cross-piece 16 and will be inserted into the loop-shaped keeper 21, which will be moved forwardly until it slides over the protuberance 23. The prongs 19 are inserted into the selected holes 24. The wrist of the wearer will exert an upward pressure on the center cross-piece 20, which pressure will be transmitted to the strip 11 located above said cross-piece. In this manner the prongs 19 will be kept securely in the holes 24 and the protuberance 23 will be urged upwardly so that it will engage the keeper 21 and will prevent the end 22 of strip 11 from slipping out of said keeper.

Having described my invention, what I claim and desire to secure by Letters Patent is:

A wrist watch strap comprising a pair of overlapping, elongated strips of thin, resilient material, a respective eye in one end of each strip for attachment of said strips to a wrist watch, an eye at the other end of one of said strips, a rectangular buckle having an end bar pivotally secured in said last-mentioned eye, a pair of parallel side bars extending from said end bar and having inwardly-turned end portions provided with respective locking prongs, and an intermediate bar secured at its ends to said side bars and substantially parallel to said end bar, said locking prongs being turned downwardly and spaced apart cross-wise of said buckle, said other strip having its end portion opposite the eye therein receivable between said inwardly-turned end portions of said side bars and said intermediate bar and provided with paired perforations spaced apart longitudinally thereof to receive said locking prongs, and a loop-shaped keeper slidable on said one strip and receiving said other strip to hold said other strip down on said intermediate bar and thereby maintain said prongs in a selected pair of said apertures, said other strip having a tapered end insertable through said loop and a protrusion thereon holding said keeper in operative engagement therewith.
